beschränkter Haftung, Friedrichshafen, Ger-
many

Application November 3, 1932, Serial No. 640,920
In Germany November 9, 1931

12 Claims. (Cl. 244—125)

My invention relates to rigid airships which are gas-inflated and has special reference to the ring bracing of such ships.

As is well known the inner space of rigid airship bodies or hulls is subdivided longitudinally into individual compartments by means of bracings which generally serve for staying the so-called ring girders in their plane. In some cases instead of using light ring girders and staying them by braces, strong girders were made use of which form a substantially circular truss without needing an inner bracing. My invention does not relate to this latter kind of construction but to rings of rigid airships with light circumferential girders and inner bracing.

This ring bracing serves also for supporting the gas pressure of the gas cell in neighbouring compartments, which may vary if the cells are not inflated to the same degree, or if the airship is longitudinally inclined, or if one gas cell is deflated for some reason. The ring bracing in such cases yields toward the side on which the gas pressure is lower or has disappeared totally. This yielding will go as far as the expansion of the stays, which may be wires or cables, allows. The wires and cables as well as the ring girders in such cases get a super load which makes it necessary to give adequate dimensions to these elements. The greatest load on the ring bracing and the ring girders occurs when one of two neighbouring compartments is deflated. To take care of such extreme loads it is necessary to make the ring girders and the staying wires and cables much stronger than their ordinary load would afford. This means a considerable additional weight in structural elements.

By my invention I reduce the loads on the girders and stays by providing a special system of stays. The stays coming from the circumference of the ring I unite in groups of three or more and lead them to two or more points near the longitudinal axis of the airship and here I provide for a connection between these points. I prefer to make this connection so that the distance between the end points of the stays near the axis of the ship can be varied. If the distance between these points is increased the bracing elements, if difference of pressure on both sides thereof exists, will yield toward the lower pressure side.

I prefer to combine this new construction according to my invention with the prior known construction of a longitudinal structural element running through the compartments of the ship near its longitudinal axis. Elements of this kind have been made use of for example in bigger airships having stayed rings, in which at the same time they served as a catwalk between the gas cells, the upper cells containing supporting gas, such as hydrogen or helium, whereas

the lower cells were inflated with a fuel gas for the engines.

By fixing the groups of stays to this longitudinal element in such manner that the length of the stays can be varied, as above explained, I gain the advantage that the total length of such stays equals nearly only the radius of the respective ring instead of the diameter, which means that they can be thinner and consequently will be lighter.

With unstayed rings net-works are provided to support the disks of the gas cells in case of overload from one side. It has been suggested to make such net-work elastic by providing yieldable or elastic elements at each ring corner to which the net-work is fastened. This means a considerable number of elastic elements which are comparatively heavy. With my new construction in connection with stayed rings I need only as many elastic elements as there are groups of stays, which may be two or preferably three. Of course in certain cases it may be advisable to have four or more groups. But generally three of them will answer the purpose.

My new way of construction means of course saving in weight, which is of greatest importance in connection with aircraft. Furthermore, a few elastic elements are much easier to control and inspect than a great number of them, especially if they are situated near a gangway or catwalk and not distributed over the entire circumference of the ring.

The elements interconnecting the end points of the groups of ring stays or braces can be such as must be operated by hand for their lengthening or shortening; but I prefer to use springs, air buffers or the like which yield automatically with the overload and cause return to the original position whenever the overload vanishes.

My invention will be understood best when having reference to the drawing which represents several examples embodying my invention.

Figs. 1 and 2 are each an elevation of an airship ring, but showing two different examples, in a diagrammatical manner.

Fig. 3 is a partial longitudinal section through an airship, corresponding to Fig. 2 and showing the normal state in which the gas cell represented (only one cell is shown, the other one is omitted) yields into the neighbouring compartment because of the airship's bow (to the left) being higher than its stern (to the right).

Fig. 4 corresponds to Fig. 3 but represents the state in which the left hand gas cell is deflated so that the right hand cell by the gas pressure is pressed into the left hand compartment thereby considerably tensioning the ring stays or braces.

Fig. 5 is an enlargement of the middle portion of Fig. 1 showing the members connecting the end points of the groups of stays.

Fig. 6 gives another example of such end connection but in combination with a longitudinal structural element.

Fig. 7 is a third example of this kind.

- 5 Between the longitudinal girders 1 of the airship the ring girders 2 are situated. There are radial braces 3 and auxiliary braces 4 connecting the ring corners with the inner end points 25 near the longitudinal axis of the airship.
- 10 In the examples represented there are formed three groups of such stays or braces 3 leading to three end points 25. The elements interconnecting points 25 and adapted to be shortened or lengthened are turn buckles 11, as shown in Figs. 15 1, 2, 3, 4, 5, and 7, respectively, or they may be springs or the like, as represented in Fig. 6. In this latter case the spring arrangements (12, 13, 14, 15) connect all three points 25 to one common middle point 35 which in the present example at 20 the same time is a corner of the longitudinal gang way 5.
- 20 In Figs. 3 and 4 the gas cell wall is indicated at 7.

25 In the cases in which turn buckles are used as interconnecting members it is necessary to loosen them to an adequate degree whenever undue superpressure or overload on the ring braces or stays occurs, and to make them tight again when such overload vanishes. If springs or other 30 yieldable elements are made use of no special operation is necessary, but, of course, the springs must be adequately chosen.

35 If there are only two groups of ring braces leading to two end points it is advisable to provide an upper and a lower group and—in case there is a longitudinal structural element—to connect the lower group to this element directly and to have the yieldable member between the upper group and the longitudinal element so that 40 the upper group of braces can give more way than the lower group which corresponds to the gas pressure distribution. Such construction could easily be obtained if in Fig. 6 the two lower groups of stays ending in members 8 and 9 were united 45 and directly fixed to gang way 5.

I do not want to be limited to the details described or shown in the drawing, as many variations will occur to those skilled in the art.

What I claim is:

- 50 1. In an airship comprising a hull having a ring member, a plurality of radially extending braces connected at their outer ends to said ring member, and a resilient means for connecting the inner ends of at least one group of a plurality 55 of said braces with others of said braces at a central location.
- 60 2. In an airship comprising a hull having a ring member, a plurality of radially extending braces connected at their outer ends to said ring member, a plurality of elements each connecting the inner ends of separate groups of said braces with one another, and separate means for connecting each of said elements with one another at a central location.
- 65 3. In an airship comprising a hull having a ring member, a plurality of radially extending braces connected at their outer ends to said ring member, a plurality of elements each connecting the inner ends of separate groups of said braces with one another and tensioning means for connecting each of said elements with one another at a central location.
- 70 4. In an airship comprising a hull having a ring member, a plurality of radially extending braces

connected at their outer ends to said ring member, a plurality of elements each connecting the inner ends of separate groups of said braces with one another and yieldable means for connecting each of said elements with one another at a central location.

5 5. In an airship comprising a hull having a ring member, a substantially axial supporting member, a plurality of radially extending braces connected at their outer ends to said ring member, a plurality of elements each connecting the inner ends of separate groups of said braces with one another, and adjustable means for connecting each of said elements with one another at a central location.

10 6. In an airship comprising a hull having a ring member, a substantially axial polygonal supporting member, a plurality of radially extending braces connected at their outer ends to said ring member, a plurality of elements each connecting the inner ends of separate groups of said braces with one another, means for connecting each of said elements with different ones of the apexes of said supporting member, and a single adjusting member for each group adapted to simultaneously adjust the tension in all of the braces in that group.

15 7. In an airship comprising a hull having a ring member, a substantially axial triangular supporting member, a plurality of radially extending braces connected at their outer ends to said ring member, a plurality of elements each connecting the inner ends of separate groups of said braces with one another, means for connecting said elements with different ones of the apexes of said supporting member, and a single adjusting member for each group adapted to simultaneously adjust the tension in all of the braces in that group.

20 8. In an airship comprising a hull having a ring member, a substantially axial triangular supporting member, a plurality of radially extending braces connected at their outer ends to said ring member, a plurality of elements each connecting the inner ends of separate groups of said braces with one another, and means for connecting each of said elements directly with the same apex of said supporting member.

25 9. In an airship comprising a rigid hull having a ring member requiring inner bracing, inner braces fixedly secured at their outer ends to the ring member, a plurality of spaced plates, the inner ends of said braces being united to said spaced plates and yielding means for securing said spaced plates to each other.

30 10. In an airship comprising a rigid hull having a ring member requiring inner bracing, inner braces fixedly secured at their outer ends to the ring member, a plurality of spaced members, the inner ends of said braces being united to said spaced members, and yieldable members connecting said spaced members.

35 11. A supporting ring for a rigid airship hull having inner braces secured at their outer ends to the ring, a plurality of spaced plates connected to the inner ends of said braces, and means yieldably securing said spaced plates to each other.

40 12. A supporting ring for a rigid airship hull having inner braces secured at their outer ends to the ring member, spaced members, the inner ends of said braces being connected to said spaced members, and yieldable members connecting said spaced members together.
